ENGELBERT A. BARTEL, OF BROOKLYN, NEW YORK, ASSIGNOR TO P-W DEVICE CORPORATION, OF BROOKLYN, NEW YORK, A CORPORATION OF NEW YORK

FEED BOARD FOR PRINTING PRESSES

Original application filed February 11, 1927, Serial No. 167,457. Divided and this application filed May 8, 1930. Serial No. 450,666.

This invention relates in general to feed boards for printing presses, and more especially to printing press feed boards used for intaglio printing.

5 This application constitutes a division of my co-pending application, Serial No. 167,457, filed February 11, 1927.

The invention still further contemplates the provision of sheet metal members adjustably secured to the feed board for regulating the size of opening in the feed board through which the impression die operates.

10 The invention also contemplates the provision of a flexible support for the card, such support consisting of metal sheets, the yieldability of which support will aid in lifting the work from the die after an impression has been taken to protect the work from possible smudging due to motion of the work 15 relative to the die as the work is released from the die.

20 These and other features, capabilities and advantages of the invention will appear from the subjoined detail description of one specific embodiment thereof, illustrated in the accompanying drawings, in which

25 Figure 1 is a plan view showing the feed board and associated elements for determining the position of the sheet edge engaging members after the trial impression has been made;

30 Fig. 2 is a plan view similar to Fig. 1, having removed therefrom the trial impression sheet, the work and two metal sheets, for determining the size of opening of the feed board;

Fig. 3 is a front elevation of the feed board; and

40 Fig. 4 is a detached elevation of one of the members for anchoring the sheet edge engaging members in place.

In the embodiment shown, there is illustrated a feed board F, preferably consisting of a light metal such as aluminum or the 45 like, and having a lower rectangular supporting member 1 and an upper sheet 2, the edges of which extend beyond the supporting member 1, as clearly indicated in Fig. 3.

As shown in Fig. 2, the upper sheet 2 has 50 two openings 3 and 4 extending therethrough,

and three elongated slots 5, 6, and 7. The opening 3 has a rectangular portion R and an extension E extending from its lower right hand edge. The portion R is formed to permit the impression die to pass therethrough into engagement with the work supported on the feed board, and the extension E is provided to permit the operator to pass his finger into the same and engage the work to remove the same from the feed board after an impression has been received. The extension E may be used for both large letter sheets and short letter sheets, envelopes, cards, and the like, although especially provided to be used for engaging short letter sheets, envelopes and cards.

The opening 4 is especially provided to permit the operator to pass his finger into the same to engage the lower right hand corner of large letter sheets.

70 The slots 5, 6, and 7 are of the same general conformation, that is, provided with an elongated slot portion 8 and enlarged openings 9 and 10 at the ends thereof, the enlarged openings 9 and 10 being preferably round, as illustrated, and communicating with the slot portion 8. In the present instance, the slots 5 and 6 are parallel with one another, the slot 6 being longer than the slot 5 and nearer the lower edge or near side of the feed board F, 75 both slots 5 and 6 being also preferably parallel to the near side of the feed board F. The slot 7, in the present instance, extends at right angles to the slots 5 and 6, and is disposed parallel to and adjacent to the right hand edge of the feed board F.

80 The portion R of the opening 3 is, of course, large enough to accommodate the average largest impression dies. It has been found in practice that sometimes one or more edges of the impression die have clinging thereto ink that was not properly removed when the impression die was wiped preparatory to forming an impression. In such cases, unless provision is made to protect the sheet 85 of work from such ink containing edge, there will, of course, be transferred to the sheet of work such ink. In the present instance, provision is made to prevent the transfer of ink from the edges of the impression dies. This 90 95 100

provision consists primarily of a plurality of metal sheets, preferably composed of planet hardened steel. Two of such sheets 11 and 12 are comparatively elongated and are 5 provided with securing means, preferably the spring clips 13 and 14 illustrated. These clips 13 and 14, clearly illustrated in Fig. 3, in the present instance, engage the left hand edge of the sheet 2 with the body portions of the 10 sheets 11 and 12 extending over the upper face of the sheet 2. The sheets 11 and 12 will, of course, be positioned relative to one another and to the portion R of the opening 3 to cover the upper and lower edges of the 15 impression die. Since in the act of wiping, the upper and lower edges of the impression die are those on which the ink is more likely to cling than on the lateral edges of the impression die, the average printer frequently 20 only uses the sheets 11 and 12. However, in case of a very high class printing job, where exceeding care should be taken, the lateral edges can be protected in a similar manner. To this end, the present invention pro- 25 vided the sheets 15 and 16, see Fig. 1, which are similarly provided with spring clips 17 and 18 respectively, as illustrated. In the present instance, the sheets 15 and 16 are attached to the plate 2 by having the clips 17 30 and 18 engage the upper edge of the plate 2. The sheets 15 and 16, by means of the clips 17 and 18, can of course be conveniently adjusted to extend over the lateral edges of the impression die to be used. In the present in- 35 stance, the sheet 15, as illustrated in Fig. 1, extends over the sheets 11 and 12, and the sheet 16 extends under the sheets 11 and 12. This is of course left to the operator, and is a matter of choice. The arrangement illus- 40 trated, however, has the advantage that since the sheet of work as a rule is passed into the printing position from the upper left hand corner in a downward right hand direction, the sheet 15 would cover the upper edge of 45 the sheet 12 and thus prevent the sheet from being accidentally obstructed by such edge while passing into printing position. Similarly, when the sheet 16 is located under the sheets 11 and 12, the left hand edge of the 50 sheet 16 will be less likely to obstruct the movement of the sheet of work into position than if the sheet 16 were located on top of the sheets 11 and 12.

In order to facilitate determining the loca- 55 tion of the sheet of work in proper relation to the impression of the die, the device now to be described has been provided. This de- 60 vice consists in the main of a sheet 19 of transparent material, preferably transparent celluloid, which likewise is provided with a spring clip 20. In the present instance, the transparent sheet 19 is secured to the upper edge of the plate 2 by means of the clip 20 so that the sheet 19 extends over the por- 65 tion R of the opening 3. In order to fix the

position of the sheet 19, the sheet 19 is prefer- 70 ably provided with two pins 21 and 22 which extend inwardly to register with the recesses 23 and 24 formed in the plate 2. When the sheet 19 is so positioned, it is ready to receive a trial impression from the impres- 75 sion die. When such trial impression 25 has been received on the sheet 19, a trial sheet of work W is placed beneath the same, and when its proper position has been determined by 80 visualizing the impression 25 on the trial impres- sion sheet 19 relative to the sheet of work W, the sheet of work W is temporarily at- 85 tached to the celluloid sheet 19 by the spring clips 26 and 27, whereupon the guides are 90 positioned in the manner now to be described.

When the sheet of work W is rectangular in contour, as is generally the case, a three point contact of course would be sufficient to determine the location of the sheet of work. 85 For this reason, in the present instance, three guides are provided, although any greater number may be used as desired de- 95 pending upon the shape of the sheet of work.

The guides consist essentially of three rods 90 28, 29 and 30, each substantially identical with one another. Each of the rods, as an instance the rod 28, has an engagement block 31 secured to the end of a flexible member 32, preferably spring steel round stock, 95 which member 32, in the present instance is secured to a piece of square drill rod 33. The rods 28 and 29, in the present instance, are secured to extend parallel with one another and vertically to the slots 5 and 6, while 100 the rod 30 is secured to extend parallel to the slots 5 and 6 and vertically to the slot 7.

When a long sheet of work W is used, the lower slot 6 is preferably used to anchor the 105 rods 28 and 29 therein to determine the position of the lower edge of the sheet of work W. In the present instance, see Fig. 1 where a short piece of work, a card, is illustrated, the upper slot 5 is used to anchor the rods 28 and 29 in place. The slot 7 is used to anchor 110 the rod 30 in place, the block 31 of which defining the position of the right hand edge of the sheet of work W. The means for an- 115 choring the rods 28 and 29 in the slot 5 are substantially identical. The anchoring 120 means 34, see Fig. 4, consists essentially of a cylindrical member 35 having two parallel recesses 36 and 37 extending parallel to one another and to the face of the cylindrical member 35. Above the recesses 36 and 37, and extending at right angles to such re- 125 cesses, there is provided an opening 38 ex- 130 tends diametrically through the cylindrical member 35 and in communication with the internally threaded opening 39, extending down axially from the upper end of the cylindrical member 35. The threaded opening 39 receives the threaded portion of the set screw 40. The anchoring members 34 are positioned in the slots 5, 6, and 7, by being

135

initially introduced through the enlarged rounded ends of such slots 9 or 10, and thereupon the recesses 36 and 37 positioned to engage the edges of the slots 5, 6 and 7.

5 With particular reference to Fig. 4, the recesses 36 and 37 of the anchoring members 34 of the rods 28 and 29, are positioned to register with the edges of the slot 5, and slid along until they are substantially in line 10 with the portion R of the opening 3. The anchoring member 34 of the rod 30 is similarly introduced into the slot 7, with its recesses 36 and 37 registering with the edges 15 of the slot 7 and the anchoring member then moved along the slot 7 until it is positioned opposite the portion R of the opening 3 and 20 preferably adjacent to the lower edge thereof, as indicated in Fig. 1. The rods 28, 29 and 30, if not already introduced into the anchoring members 34, may then be slid into 25 the anchoring members 34 with their blocks 31 extending toward the portion R of the opening 3.

After the sheet of work W has been temporarily anchored by the clips 26 and 27, as 25 illustrated in Fig. 1, the rods 28 and 29 are moved up until they engage the lower edge of the sheet of work W, whereupon the set-screw 40 is manipulated to tightly anchor 30 the rods 28 and 29 in such position. Similarly, the rod 30 will be moved into position 35 so that its block 31 engages the right hand edge of the sheet of work W, and thereupon its set screw 40 is manipulated to engage the rod 30 and securely anchor it in position. By reference to Fig. 3, it will be noted that the flexible member 32 is bowed downward toward the plate 2. In view thereof, when the set screw 40 is screwed down, the rods 28, 40 29 and 30 will tend to straighten out the curve in the flexible portion 32, thereby tightly anchoring the blocks 31 in engagement with the surface beneath the same. The openings 38, as indicated in Fig. 4, preferably afford sufficient clearance for the rods 28, 29 and 30, so that the same can be freely moved in the cylindrical portions 35 when the screws 40 are loosened, and in turn when the screws 40 are loosened they also permit 50 the blocks 31 to lightly engage the surfaces from beneath.

As illustrated in Fig. 1, the metal sheet 12 also serves as a support for the blocks 31, 31, when a short sheet of work, such as the 55 card W is used, it being obvious that without such support 12 the blocks 31 would extend into the opening 3. Similarly, the sheet 16 will serve as a support for the block 31 of the rod 30 when a narrow piece of work 60 is used.

After the rods 28, 29 and 30 are so locked in position, the sheet of celluloid 19 with its thereto attached sheet of work W may be removed, and the feed board is then prepared 65 to receive the work for the printing job. In

the printing operation, the piece of work W is preferably fed down from an upper left hand position downwardly in a right hand direction, so that its lower edge and right hand edge engage the blocks 31 of the rods 28, 29 and 30. After the impression has been taken, the lower right hand corner of the sheet of work is generally engaged to remove the piece of work W in a right hand direction. When the metal sheet 16 is not in use, the extension E forms a clearance along the right hand edge of the piece of work W, so that the finger of the operator may extend into the same and thus conveniently engage the right hand edge of the piece of work W and remove it therefrom after the impression has been received. On the other hand, when a long piece of work is used, such as a standard letter size sheet, a portion of the right hand edge will extend across the opening 4, in which case the opening 4 will serve to permit the operator's finger to pass into the same and engage the right hand edge of the sheet to remove it after the impression has been received.

It is obvious that various changes and modifications may be made to the details of construction without departing from the general spirit of the invention as set forth in the appended claims.

I claim:

1. The combination with a feed board having an opening therein for the operation of the impression die and having a flange along its edge, of a plurality of supporting metal sheets, and spring clips formed on the edges of said sheets to engage the flange of said feed board, said supporting sheets serving to extend across the paths of movement of the edges of the impression die and being adjustably mounted by said clips to facilitate positioning such supporting sheets to accommodate various sizes of impression dies.

2. The combination with a feed board having an opening therein for the operation of the impression die, of a plurality of clearances in said feed board adjacent to said first mentioned opening to permit the fingers of the operator to pass into said clearances to engage the work preparatory to removing same from the feed board.

3. The combination with a feed board having an opening therein for the operation of the impression die and having a flange along its left hand edge, of two supporting metal sheets, and a spring clip formed on one end of each of said sheets to engage said flange to permit said sheets to extend across the face of said feed board to cross the paths of movement of the upper and lower edges of the impression die, said sheets being adjustably mounted on said feed board by means of said clips to facilitate positioning such supporting sheets to accommodate various sizes of impression dies.

4. The combination with a feed board having an opening therein for the operation of the impression die and having a flange along its left hand edge and its upper edge, of four supporting metal sheets, and a spring clip formed on one end of each of said sheets, two of said sheets having their clips engage the left flange of said board to permit the sheets to extend across the face of said board to cross the paths of movement of the upper and lower edges of the impression die, the other two of said sheets having their clips engage the upper flange of said board to permit said sheets to extend across the face of said board to cross the paths of movement of the lateral edges of the impression die, said sheets being adjustably mounted on said feed board by means of said clips to facilitate positioning such supporting sheets to accommodate various sizes of impression dies.
5. The combination with a feed board having an opening therein for the operation of the impression die and having a flange along its edge, of a plurality of supporting sheets composed of planet hardened steel, and clips formed on the edges of said sheets to engage the flange of said sheets to engage the flange of said feed board, said supporting sheets serving to extend across the paths of movement of the edges of the impression die and being adjustably mounted by said clips to facilitate positioning such supporting sheets to accommodate various sizes of impression dies.
6. The combination with a feed board composed of sheet metal having an opening therein to accommodate the impression of the impression die, there being a plurality of slots in said board, guide means adjustably mounted in said slots to determine the location of the sheets of work relative to the feed board during the printing operation, and supporting sheets of metal secured to said feed board to cross the paths of movement of the edges of the impression die and form supporting surfaces for said guide means, said guide means having flexible portions intimately to engage the adjacent supporting sheets and thus be anchored in said feed board against displacement.
7. The combination with a feed board having an opening therein for the operation of the impression die, of a clearance in said feed board forming a lateral extension from said opening to permit the finger of the operator to pass into said clearance to engage the work preparatory to removing the same from the board.

ENGELBERT A. BARTEL.
